UNITED STATES PATENT OFFICE.

THOMAS CECIL KING, OF PURVIS, MISSISSIPPI.

AUTOMATIC SAFETY-SWITCH.

No. 926,575.

Specification of Letters Patent.

Patented June 29, 1909.

Application filed August 31, 1908. Serial No. 451,026.

To all whom it may concern:

Be it known that I, THOMAS CECIL KING, a citizen of the United States, residing at Purvis, in the county of Lamar and State of Mississippi, have invented a new and useful Automatic Safety-Switch, of which the following is a specification.

The invention relates to improvements in automatic safety switches.

10 The object of the present invention is to improve the construction of automatic safety switches, and to provide a simple, inexpensive and efficient construction, adapted to be readily applied to various switches and capable, should a switch be carelessly left open, of enabling the same to be automatically closed by an approaching train, thereby eliminating the accidents resulting from trains running into open switches.

20 A further object of the invention is to provide an automatic railroad switch of this character, adapted, when a train leaves a siding and enters the main line, of automatically closing the switch after the train, thereby effecting a great saving of time and obviating the necessity of stopping the train and waiting while a train hand returns to and closes and locks the switch.

25 The invention also has for its object to provide a switch, adapted to be automatically closed by approaching trains, thereby avoiding the expense of equipping switches between stations with signal lights for indicating the position of the rails at night.

30 With these and other objects in view, the invention consists in the construction and novel combination of parts hereinafter fully described, illustrated in the accompanying drawings, and pointed out in the claims 35 hereto appended; it being understood that various changes in the form, proportion, size and minor details of construction, within the scope of the claims, may be resorted to without departing from the spirit or sacrificing any of the advantages of the invention.

35 In the drawings:—Figure 1 is a plan view of an automatic safety switch, constructed in accordance with this invention. Fig. 2 is a side elevation of the same. Fig. 3 is a transverse sectional view on the line 3—3 of Fig. 1. Fig. 4 is a sectional view on the line 4—4 of Fig. 1. Fig. 5 is a horizontal sectional view on the line 5—5 of Fig. 2. Fig. 6 is a vertical sectional view on the line 6—6 of Fig. 7. Fig. 7 is a vertical sectional view on the line 7—7 of Fig. 1. Fig. 8 is a detail sec-

tional view on the line 8—8 of Fig. 2, illustrating the manner of mounting the track levers.

Like numerals of reference designate corresponding parts in all the figures of the drawings.

1 and 2 designate movable switch rails, connected by tie bars 3 and 4 and operating in conjunction with main line rails 5 and 6 and siding rails 7 and 8 in the usual manner. The movable switch rails are operable by hand to throw the switch for the siding, and the operating mechanism comprises in its construction a switch stand and connections 60 between the same and the tie bar 3. The switch stand is composed of an upright tubular casing 9 and a vertical shaft 10, journaled in suitable bearings and provided at its lower end with a crank arm 11. The crank arm is 65 connected by a link or rod 12 with the adjacent end of the tie rod 3, and it is designed to be of the desired length and to extend in the desired direction to secure the necessary movement of the switch rails. The upper 70 end of the vertical shaft is equipped with the ordinary signal or target 13 for indicating whether the switch is open or closed, and as the switch is adapted to be automatically closed by the means hereinafter described, 75 it is unnecessary to equip switches between stations with a signal light for indicating at night whether the switch is open or closed. This will avoid the expense incident to ordinary switches where such signal lights are 80 necessary.

85 The switch shaft is provided at its upper portion with a horizontal arm 14, having an outer operating lever or member 15, pivoted in a bifurcation of the arm 14 and adapted to swing downward by gravity into engagement with a notch 16 of the top plate of the casing of the switch stand. The switch stand is 90 equipped with a lock 17 having a spring actuated bolt, or other means for automatically engaging the pivoted member or lever 15 of the arm 14, when the said pivoted lever or member is swung downward into the notch 16. As any construction of key operated lock may be employed for this purpose, 95 a detail description and illustration thereof is deemed unnecessary.

100 The switch, which is locked in its open position by the means hereinafter described, is automatically closable when released from such locking mechanism, and this automatic closing of the switch is effected by springs 105

18 and 19. The spring 18, which is of helical form, encircles the vertical shaft 10, its upper end 20 being secured in a perforation of a fixed L-shaped bracket 21, fastened to the 5 casing of the switch stand and arranged interiorly thereof, as clearly illustrated in Fig. 3 of the drawings. The lower end 22 of the spring 18 is secured to a lug 23 of a collar 24, clamped to the lower portion of the shaft 10 by means of a set screw 25. The set screw 10 adjustably connects the lower end of the spring with the shaft, and it enables the tension of the spring to be controlled. The spring is adapted to produce a positive 15 rotary movement of the vertical shaft 10 when the switch closes, so that there is no liability of the crank arm at the lower end of the vertical shaft being accidentally thrown to a dead center and interfering with the 20 automatic closing of the switch. The spring 19, which is located at one side of the track, is interposed between a supporting bar 26 and a lever 27. The supporting bar 26, which is curved, extends across the space 25 between two cross ties and is secured to the same, as clearly shown in Fig. 1 of the drawings, and it is provided at one end with an arm 28 to which the lever 27 is pivoted. The lever 27, which is arranged in substantial 30 parallelism with the supporting bar, is connected at one end to the arm 28 and its other end is pivoted to the adjacent end of the tie bar 5. The lever is provided at an intermediate point with a socket 29, receiving 35 one end of the spring 19, which is arranged horizontally. The other end of the spring is engaged by an adjusting screw 30, mounted in a threaded opening 31 of the supporting bar and engaging the outer end of the 40 spring. The inner end of the adjusting screw is provided with a head for engaging the spring, and the outer portion of the screw receives a lock nut 32 for securing the screw in its adjustment. The opening movement of 45 the switch carries the lever 27 outward in a direction of the supporting bar 26, and the coiled spring 19 is thereby compressed and is adapted, when the switch rails are free to move, to coöperate with the spring 18 and 50 automatically close the switch.

The operating arm of the switch and the pivoted lever or member thereof are arranged in front of the switch stand when the switch is closed, as illustrated in Fig. 1 of the drawings, and it is swung from such position to the dotted position in Fig. 2 to open the switch. The switch is locked in its open position by a latch consisting of a vertically movable locking bar 33, mounted in suitable 55 upper and lower guides 34 and 35 of the switch stand and projecting through an aperture 36 of the top or cap plate. The upper portion of the locking bar is flat to prevent rotary movement, and the lower portion 60 37, which operates in the lower guide 35

is round and receives a coiled spring 38, disposed on the locking bar and interposed between the lower guide 35 and a collar 39, fixed to the rounded portion of the locking bar, but any other suitable means may be 65 employed for guiding the upper end of the coiled spring. The upper end 40 of the locking bar is beveled to present an inclined front edge or face and a rear shoulder. The beveled edge or face is arranged to be engaged by 70 the operating arm of the switch stand in the movement of the same away from the notch or recess 16 in opening the switch, and in such opening movement the operating arm is adapted to depress the locking rod, which 75 automatically engages the operating arm when the latter passes the upper end 40, as clearly illustrated in Fig. 6 of the drawings. The locking rod is adapted to hold the switch open until it is disengaged from the operating 80 arm either by the train actuated mechanism hereinafter explained, or by the means of a handle 41, extending from the upper portion of the locking rod and arranged in a vertical slot 42 of the casing of the switch stand. If, af- 85 ter a train takes a siding, it is desired to close the switch by hand, the handle 41 is moved downward in the slot 42, thereby withdrawing the upper end of the locking bar from its engagement with the operating arm of the 90 switch stand and permitting the switch to close.

The train operated mechanism for automatically closing the switch includes a pair of vertical levers 43, pivoted to suitable supporting brackets 44 and connected with an outer arm 46 of a transverse rock shaft 47, extending beneath the track and connected with the locking bar. The bracket 44 consists of a substantially vertical body portion, 10 provided with horizontal arms 48, which are secured to the upper faces of the adjacent cross ties, the body portion of the bracket being preferably located between the space of the cross ties, as clearly shown in Fig. 2 of the 11 drawings. The lever 43 is pivoted at an intermediate point to the upper portion of the bracket, and its lower arm 49 is provided with a projection or lug 50, which is connected to the upper end of a coiled spring 51. 115 The coiled spring 51, which is arranged vertically, is secured at its lower end to a lug 52, extending horizontally from the lower end of the body of the bracket. The spring 51 permits the lever 43 to oscillate in either direction, and it normally maintains the track lever 43 in a perpendicular position. The connections 53 between the track levers and the outer arm 46 of the transverse rock shaft 120 preferably consist of tubular rods, such as 125 usually are employed in such connections, and suitable anti-friction rollers or wheels 54 are designed to be provided for supporting the connections 53, the track levers being designed to be located a sufficient distance 130

from the switch to insure perfect safety in the operation of the latter by an approaching train.

The rock shaft 47, which is journaled in suitable bearings, is equipped at its inner end with a pair of oppositely extending arms 55, connected by a pair of chains 56, or other suitable flexible connections with the lower end of the locking rod. The duplicate arms 55 and chains 56 permit an operation of the releasing mechanism by a train approaching a switch from either direction. When a rock shaft is rotated in either direction, one of the arms 55 will pull downward on its chain and withdraw the locking rod from engagement with the operating arm of the switch stand, and when the rock shaft is rotated in the other direction, the other arm 55 will release the switch and permit the same to automatically close.

When it is desired to run a train on a siding, it is necessary to open the switch by hand and after the train has taken the siding, another train will automatically close the switch should the latter have been carelessly left open by the train on the siding. Trains are designed to be equipped at suitable points, such as the opposite sides of a locomotive and the opposite sides of the rear car with a tripping lever 57, adapted to be set to engage the track levers. The tripping levers 57, which may be of various constructions, are preferably pivoted at an intermediate point to a bracket or support 58, and is equipped with a spring actuated dog or detent 59 for engaging a notched segment 60, whereby the tripping lever is positively locked in position for operating the track levers, or in a position to clear the same. By setting the tripping levers 57 to engage the track levers, the train will operate the track levers and will close the switch should the same be open. This will obviate the necessity of employing signal lights between stations for indicating whether the switches are open or closed, and will thereby lessen the expense of manipulating railroads. By equipping the rear cars of a train with setting levers, a train may be run from the siding onto the main line, and the switch will be automatically closed by the rear car, thereby avoiding the delay of stopping the train while a train hand returns to the switch and closes and locks the same. This will be found especially advantageous on grades where it is difficult to start a train after stopping the same. By equipping a train at each side with tripping levers, it will be adapted to operate switches having the track levers located at either side of the track.

The switch stand and the other mechanism of the automatic switch may be located at either side of the track to suit railroads and their requirements.

Having thus fully described my invention,

what I claim as new and desire to secure by Letters Patent, is:—

1. The combination with an automatically closable switch including a switch stand having operating means, of a latch mounted on the switch stand for holding the switch in an open position, and train actuated means for operating the latch to withdraw the same from its engagement with the operating means of the switch to release the latter. 70

2. The combination with an automatically closable switch including a switch stand having an operating arm, of a spring actuated latch mounted on the switch stand and located in the path of the operating arm for locking the switch open, and train actuated means for operating the latch to withdraw the same from engagement with the switch arm to permit the switch to close. 75

3. The combination with an automatically closable switch including a switch stand, means for connecting the switch stand with the switch, a lever pivoted to such connecting means, a support arranged in spaced relation with the lever, and a spring interposed between the support and the lever for actuating the latter, of a latch for holding the switch in its open position, and train actuated means for operating the latch to close the switch. 85

4. The combination with an automatically closable switch including a switch stand, means for connecting the switch stand with the switch, a lever connected with the said means and provided with a socket, a support arranged in spaced relation with the socket 100 and the lever, a spring interposed between the lever and the support and having one end fitted in the socket, and an adjusting device mounted on the support and receiving the other end of the spring for regulating the 105 tension of the latter.

5. An automatically closable switch including a switch stand, means for connecting the switch stand with the switch, a support arranged to extend across the space between two cross ties and provided at one end with an arm and having a threaded aperture at an intermediate point, a lever pivoted to the arm and connected to the said means, a spring interposed between the 110 lever and the support, and an adjusting screw mounted in the threaded aperture 115 and arranged to engage the tension thereof.

6. An automatically closable switch including a switch stand having a shaft and provided with operating means, a coiled spring disposed on the shaft and connected with the same, means for connecting the switch stand and the switch, a support, a lever mounted on the support and connected with the said means, and a spring interposed between the support and the lever for actuating the latter. 120

7. The combination with an automatically closable switch including a switchstand 125

having operating means, of a latch for locking the switch in an open position, a rock shaft having opposite arms flexibly connected with the latch and adapted to be 5 rocked in either direction for releasing the switch, and train actuated means for rocking the said shaft.

8. The combination with an automatically closable switch including a switch stand having an operating arm, of a vertically movable spring actuated latch mounted on the switch stand and arranged in the path of the operating arm for locking the switch in its open position, a rock shaft provided with opposite arms, a pair of flexible connections extending from the arms to the rod, and train actuated means for rotating the rock shaft.

9. The combination with an automatically closable switch including a switch stand having an operating arm, of a vertically movable spring actuated latch mounted on the switch stand and arranged in the path of the operating arm for locking the switch 25 in its open position, a rock shaft provided at one end with opposite arms flexibly connected with the latch, said rock shaft being also provided at the other end with an arm, and track levers connected with the latter 30 arm and arranged to be operated by a train.

10. The combination with an automatically closable switch, of a latch for holding the same in its open position, a rock shaft connected with the latch, a bracket provided 25 with opposite arms for mounting it between two cross ties, a track lever pivoted at an

intermediate point to the bracket and extending upwardly therefrom, a spring connecting the lower portion of the lever with the bracket, and connections between the lever and the rock shaft.

11. The combination with an automatically closable switch, of a latch for holding the switch in its open position, a supporting bracket composed of a substantially vertical body portion provided at opposite sides with arms, said bracket being also provided at the bottom of its body portion with a lug, an upright lever pivoted to the body portion of the bracket, a coiled spring connected with 4 the lower portion of the lever and with the lug of the bracket, and means for connecting the lever with the latch.

12. The combination with an automatically closable switch including a switch stand 5 having an operating arm, of a spring actuated latch mounted on the switch stand and arranged in the path of the operating arm for locking the switch in its open position, said latch being provided with an operating 6 handle projecting exteriorly of the switch stand, and train actuated means connected with the latch for automatically releasing the operating arm of the switch.

In testimony, that I claim the foregoing as 6: my own, I have hereto affixed my signature in the presence of two witnesses.

THOMAS CECIL KING.
